A. James

United States Patent Office.

ARTHUR JAMES, OF REDDITCH, ENGLAND.

Letters Patent No. 83,284, dated October 20, 1868.

IMPROVEMENT IN ENVELOPES FOR NEEDLES.

The Schedule referred to in these Letters Patent and making part of the same.

To all to whom it may concern:

Be it known that I, ARTHUR JAMES, of Redditch, in the county of Worcester, England, needle-manufacturer, a subject of the Queen of Great Britain, have invented or discovered new and useful "Improvements in Needle-Cases and Wappers," and I, the said ARTHUR JAMES, do hereby declare the nature of the said invention, and in what manner the same is to be performed, to be particularly described and ascertained in and by the following statement thereof; that is to say—

My invention consists of a needle-case made of paper, folded and pasted in the form of a flat tube, open at both ends. One end of the flat tube is cut away on one side, and the remaining side is made of a nearly semicircular figure, and constitutes a flap. When the flat paper tube is folded near its middle, the before-mentioned flap can be inserted in the open end of the tube, thus forming a flat case.

The needles, stuck upon paper or fabric in the ordinary way, are introduced into the open case at the end on which the flap is formed, the front of the inner side of the case at that part being cut away, the said cut-away part having a nearly semicircular figure, to permit of the ready removal, when the case is open, of the needles from the paper or fabric in which they are stuck.

A piece of paper, cut in the manner described, but without having its edges pasted together, may be employed as a wrapper in which to enclose needles.

In making a needle-case according to this part of my invention, I take a blank or piece of paper, of the form represented in Figure 1 of the drawing. The said blank consists of a rectangular piece of paper; the tops of the side pieces *a* *b* of which are cut away, and the top, *c*, of the middle part, *c*, is made of a nearly semicircular figure, and constitutes a flap.

By folding the side pieces *a* *b*, of the blank, fig. 1, at the vertical lines *d* *e*, upon the middle part *c*, and pasting the said edges of the side pieces *a* *b* together, a flat tube, open at both ends, is formed, as illustrated in Figure 2, the said tube having a flap, *c*, at the top of one side, and a nearly semicircular opening, *f*, at the top of the other side of the said tube.

By folding the tube, fig. 2, at about its middle, that is, at the line *g*, a flat case, and represented in elevation and edge view in Figure 3, is formed, the flap *c* being capable of being inserted in the open end of the case, so as to securely close the case.

The needles to be held in the case are stuck upon a piece of fabric or paper, and enclosed in a wrapper or covering of the kind represented in Figure 4. This wrapper consists of a strip of paper somewhat longer than the needles to be covered, the top being formed into a flap, *h*.

The needles being laid upon the paper, fig. 4, the flap *h* and bottom piece *i* are folded upon the needles, as illustrated in the edge view, and the needles thus covered or wrapped up, are introduced through the opening *f* into the case, fig. 2, where the upper parts of the needles are represented broken off, for the purpose of exhibiting the opening *f* in the case.

By now folding the case at its middle, *g*, and inserting the flap *c* in the open end of the case, the said case is closed, and the needles are securely fixed therein.

To gain access to the needles in the case, the flap *c* is removed from the end of the case, and the case opened, as illustrated in fig. 2, when, by lifting the wrapper in the case, and raising its flap, *h*, the needles may be removed from the fabric in which they are stuck.

The needles stuck upon fabric or paper may be placed in the case without a cover or wrapper, but I prefer to use a cover or wrapper.

By leaving the edges of the folded parts of the tube, fig. 3, unpasted, the said tube may be employed as a wrapper in which to enclose needles.

Instead of making the case square, it may be made of an oblong form, as illustrated in Figures 5, 6, and 7, fig. 5 representing the blank, fig. 6 the tube or case made from the said blank, and fig. 7 the folded flat case.

Having now described my invention, and the manner in which the same is or may be carried into effect, What I claim, and desire to secure by Letters Patent, is—

A needle-case or wrapper, made from a blank, formed and folded as herein described, and illustrated in the accompanying drawings.

ARTHUR JAMES. [L. S.]
